INTERLOCKING NUT ENGAGING INSERTS
FOR SOCKET WRENCHES AND BOX END
WRENCHES

Celia L. Phipps, Waterloo, Ill.

Application July 20, 1946, Serial No. 685,217

1 Claim. (Cl. 81—185)

1

This invention relates to improvements in interlocking socket and box end type wrenches and inserts therefor.

An object of the invention is to provide an improved construction of nested and interlocking nut engaging inserts for socket and box end type wrenches.

Another object of the invention is to provide an improved construction of nested and interlocking nut engaging inserts for socket and box end type wrenches which will be similarly formed with the exception that the inserts for the socket type wrenches are closed at one end and formed with square apertures therethrough for receiving and positioning the square shank of the handle operating member.

A further object of the invention is to provide a plurality of concentrically disposed nested nut engaging inserts for socket and box end type wrenches which will interlock with each other and with said wrenches.

Another object of the invention is to provide an improved construction of nested and interlocking nut engaging inserts for socket and box end type wrenches which will be highly efficient in operation, and relatively inexpensive to manufacture and produce.

Other objects will appear as the description proceeds.

In the accompanying drawings, which form a part of this application,

Figure 1 is a plan view of a socket wrench;

Figure 2 is a vertical sectional view through a socket wrench with nested nut engaging inserts therein;

Figure 3 is a bottom plan view looking into the open or bottom end of a socket wrench with the inserts removed;

Figure 4 is a bottom plan view of the largest nut engaging insert adapted to be received in said socket wrench;

Figure 5 is a bottom plan view of the middle-size nut engaging insert adapted to be received within said larger nut engaging insert;

Figure 6 is a side elevation of the middle-size nut engaging insert;

Figure 7 is a bottom plan view of the smallest-size nut engaging insert adapted to be received within said middle-size nut engaging insert;

Figure 8 is a sectional view taken on the line 8—8 of Figure 5;

Figure 9 is a plan view of a double ended box and wrench with nut engaging inserts removed; and

2

Figure 10 is a sectional view through one end of the box and wrench.

Like characters of reference are used throughout the following specification and accompanying drawings to designate corresponding parts.

In carrying out the invention, there is provided a socket type wrench having a cylindrical body 1, the same being closed by the thickened wall 2 at its upper end, and formed with the square aperture 3 to receive the largest square shank 4 on the end of the handle operator 5. A series of stepped square shanks 6, 7 and 8 will be formed integrally with the square shank 4 and will be arranged in axial alignment therewith. As seen from Figure 2 of the drawings, the handle operator 5 will be disposed at right angles to the said stepped shanks.

The inner annular surface of the wrench body 1 is formed with a series of alternate vertically arranged V-shaped recesses 9 and inwardly extending ribs 10, while vertical locking slots 11 are formed in alternate ribs 10.

A series of nut engaging inserts 12, 13 and 14 are provided and each comprises a vertical wall 25 made with alternate inwardly and outwardly extending ribs 15 and 16, which will be interlocked with the recesses 9 and ribs 10 formed in the wrench body 1. Alternately arranged vertical interlocking ribs 17 and slots 18 are formed on the 30 outside and inside surfaces of the inserts, whereby the inserts will interlock with the adjacent inserts. The smallest insert 14 will be provided only with the ribs 17, the slots 18 being omitted for obvious reasons.

From the foregoing description it will be apparent that each insert will be adapted to be used with varying sizes of nuts, either square or hexagonal in shape. Furthermore, each insert 8, 9 and 10 will be closed at its upper end and will be formed with the square apertures or sockets 19, 20 and 21 respectively, in which the square shanks 6, 7 and 8 will be received.

The inserts which are not to be used, as for example when the largest insert only is to be used, may be knocked out with little or no effort.

In Figures 9 and 10, a double box end type wrench is shown having a centrally disposed handle 22 and the box ends 23 and 24 formed on the opposite ends thereof. Similar inner surface construction for the box ends will be provided as shown for the socket wrench 1, and similar nesting and interlocking inserts will be used except that the inserts will be cylindrical and open at both ends.

While the preferred embodiment of the instant

invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

A wrench tool comprising a series of nested interlocking socket members each provided with an axial non-circular opening, which openings are of decreasing diameters, irregular interlocking ribs and grooves formed respectively on the inner and outer surfaces of the socket members and a handle actuator provided with a projecting end portion having a series of stepped axially aligned non-circular shank portions formed thereon, which shank portions are adapted to be inserted

respectively in the complementary aligned openings of the socket members.
